(57) CLAIM

The ornamental design for an undergarment as shown and described.

DESCRIPTION

FIG. 1 is a top, back, left perspective view of a first embodiment of the claimed design for an undergarment; FIG. 2 is a top view thereof; FIG. 3 is a bottom view thereof; FIG. 4 is a front view thereof; FIG. 5 is a back view thereof; FIG. 6 is a left view thereof; FIG. 7 is a right view thereof; FIG. 8 is an enlarged partial view of FIG. 2; FIG. 9 is a top, back, left perspective view of a second embodiment of the claimed design for an undergarment; FIG. 10 is a top view thereof; FIG. 11 is a bottom view thereof; FIG. 12 is a front view thereof; FIG. 13 is a back view thereof; FIG. 14 is a left view thereof; FIG. 15 is a right view thereof; and, FIG. 16 is an enlarged partial view of FIG. 10. The dot-dash broken lines depict boundaries of the claimed design and form no part thereof. The dashed broken lines showing the undergarment depict environmental structure and form no part of the claimed design.

1 Claim, 12 Drawing Sheets
